SLICING MACHINE

Alexander Edwin Paterson, Peckham, London,
EnglandApplication May 10, 1934, Serial No. 724,979
In Great Britain May 13, 1933

7 Claims. (Cl. 146—102)

This invention relates to slicing machines in which a piece of bacon or the like substance is advanced towards the slicing knife by means of a feed mechanism, and in which automatic means are provided for varying periodically the angular position of the piece in relation to the knife by a correcting motion, to compensate for any convergence of the two ends of the piece by a lengthwise taper in the thickness of the slices, as described in U. S. Patent No. 1,638,362.

The present invention has for its objects to provide improved controlling means for producing the angular correcting motion, to enable simple adjustment of the controlling means according to the shape of the particular piece to be sliced, to distribute the taper uniformly over all the slices into which the piece is cut, and to make the controlling means readily adaptable to existing machines of a well known type.

The invention is hereafter described with reference to the accompanying drawings, in which:—

Fig. 1 is a side elevation showing the main parts of a slicing machine provided with controlling means according to one embodiment of the invention for producing the angular correcting motion.

Fig. 2 is a plan view.

Fig. 3 is a similar view showing the controlling means adjusted to suit an angular or wedge-shaped piece of bacon.

Figs. 4 and 5 are views corresponding to Figs. 1 and 2, showing a modified construction of the controlling means.

Referring to Figs. 1 and 2, the carriage *a* of the machine reciprocates upon the base *b* and supports the feed table *c* which advances periodically towards the plane of the rotary cutting knife *d*, in the usual manner. Upon the feed table there is mounted by means of the usual pillars *e* a frame *f* having lugs *f*¹ *f*² for engaging the pillars, one of the lugs being provided with a suitable catch *f*³.

The meat-plate or holder *g* supporting the substance to be sliced is pivoted on the frame *f* upon a vertical pivot *h* towards the side of the feed table remote from the cutting knife *d*, while a controlling lever *i* is pivoted on the frame *f* upon a vertical pivot *j* towards the opposite side of the feed table; the lever *i* is shown as a straight bar secured to a segment *i*¹ fitting upon the pivot pin *j*, with a curved slot *i*² formed in this segment. The meat-plate *g* and lever *i* are connected together by a link *k* extending rearwardly from the meat-plate from a point *g*¹

at about the middle of the length of the latter, the rear end of this link being pivoted upon a connecting pin *k*¹, the upper part of which engages in the slot *i*² and is fitted with a wing nut *k*² for locking it at any position along the slot. 5

The free end of the lever *i* can swing over the top of the pivot *h*, which may be provided with a milled nut *h*¹ for temporarily clamping the meat-plate *g*. A stop *l* consisting of a vertical post, mounted upon the reciprocating carriage, extends above the top of the pivot *h* so as to form an abutment for the lever *i* as it swings forward; this post is shown as carried by a clamp *l*¹ secured by screws *l*² upon the usual horn member *m* supporting the rind or underside of the piece of bacon close to the cutting knife. As can be seen in Fig. 2, the slot *i*² is curved to a radius struck from the point *g*¹ when the meat-plate *g* is drawn back to normal position, by the engagement of the lever *i* with the stop *l*; this implies that the meat-plate will always reach its normal position at the same angular position of the lever *i*, irrespective of the position of the pin *k*¹ in the slot *i*².

In setting up an angular piece of bacon for cutting into tapering slices as indicated in dotted lines in Fig. 3, the substance *x* will be fixed on the meat-plate *g* by the usual hooks or prongs (not shown) engaging in the end of the piece, and the meat-plate then swung forward around its pivot *h* into an oblique position so as to bring the front face of the piece *x* parallel with the knife *d*; the meat-plate or holder *g* can be temporarily clamped in this position, by tightening the milled nut *h*¹ on the top of its pivot pin, 35 while the feed table is adjusted to bring the piece *x* up to the knife *d*, as seen in Fig. 3. During the swinging of the meat-plate, the link *k* will have drawn forward the controlling lever *i* to an amount depending upon the adjustment of the connecting pin *k*¹ in its slot; if for example the pin occupies the extreme end of the slot, as in Fig. 2, the lever *i* will turn through approximately the same angle as the meat-plate, though in the contrary direction. This forward 45 movement of the lever *i* is then completed by pushing the connecting pin *k*¹ along its slot (after releasing the wing nut *k*²) towards the pivot *j* of the lever *i*, until the free end of the latter abuts against the post or stop *l* on the reciprocating carriage; when the lever strikes the stop *l*, the connecting pin *k*¹ can be pushed no further along its slot. If, on the other hand, the pin *k*¹ has been left at a position too near the pivot *j*, then the lever *i* will turn through a 55

greater angle than the meat-plate, and it may strike the stop l before the front face of the piece x comes into the plane of the knife; in this case, the pin k^1 must be pulled back along the 5 slot, away from the pivot j , and subsequently re-adjusted to complete the forward movement of the lever, as described above, after the feed table has been advanced to the slicing position. The pin k^1 is then locked at the correct position 10 by tightening its nut k^2 , and the clamping nut h^1 of the meat-plate pivot can be released.

During the cutting operation, as the frame or attachment f is advanced with the feed table c , the lever i is gradually forced back by the stop l , 15 thus causing the connecting pin k^1 and link k pivoting thereon to draw back the meat-plate or holder g until it comes parallel with the knife d for the cutting of the last slice at the moment when the lever i reaches its original position, as 20 in Fig. 2; the link k can then be returned to its normal position at right angles to the meat-plate g , in readiness for the next operation, by releasing the wing nut k^2 and sliding the connecting pin k^1 along the slot i^2 , which now lies once more 25 concentric with the fixed connecting pin g^1 on the meat-plate.

The meat-plate or holder g can be locked in the closed position, when it is not desired to cut taper slices, by means of a catch f^4 pivoted on the frame f and adapted to engage a peg g^2 on the top of the holder; the catch is operated by a handle f^5 and held in either of its two positions by a flat spring f^6 secured to the frame f and pressing against one of two flat surfaces f^7 f^8 on 35 the edge of the catch. Fig. 2 shows the catch f^4 in the locked position, but it will be disengaged, as seen in Fig. 3, during the cutting of taper slices.

In a modified construction, illustrated in Figs. 40 4 and 5, the controlling lever i^4 is mounted further to the rear of the meat-plate or holder g and arranged to engage the fixed stop l^3 indirectly by means of a sliding tappet rod o guided in a bush o^1 adjacent to the frame lug f^3 engaging 45 one of the usual pillars or uprights e on the feed table c , the rear end of this tappet carrying a block p slideable along a fixed guide rod q parallel to the tappet o ; the free end of the controlling lever i^4 is forked at i^3 to engage a reduced central 50 part of the block, so that the tappet when in contact with the fixed stop l^3 will hold back the lever i^4 in relation to the advancing feed table, thus causing the link k^3 to swing the meat-plate g back to its normal position as in the embodiment 55 previously described. The curved slot i^5 for connecting the link k^3 to the controlling lever may be formed in a segment secured thereto, as in the previous case, or it may be accommodated in the width of the lever i^4 by setting the latter 60 at a suitable angle (as shown in Fig. 5) and extending the link k^3 and the tappet rod o to the required length.

Means may be provided for locking the holder g in the closed position, when taper slicing is not 65 required, for example by a detent r rocking in a groove p^1 upon the bottom portion of the block p ; the fixed guide rod q extends through a hole r^1 in this detent, and a spring r^2 normally forces the 70 detent to an inclined position in which the guide rod jams in the hole, thereby preventing the tappet rod o from advancing but allowing it to be drawn back as the holder closes against the frame. By pinching the top of the detent r 75 against a finger plate p^2 on the block p , the lock

can be released, allowing movement of the tappet in either direction.

What I claim is:—

1. In a slicing machine having a knife, a feed table, mechanism for advancing said feed table 5 in relation to said knife, and a holder mounted on said feed table for the substance to be cut by said knife, means for controlling the angular position of said substance in relation to said knife, comprising a lever extending across said feed table, a pivot for said lever towards one side of said feed table, a stop for said lever at the other side of said feed table, a pivotal connection between said holder and said feed table, and a link connecting said holder to said lever, said link extending from a point on said holder remote from said pivotal connection and in a direction away from the cutting plane of said knife to a point on said lever adjustable in relation to its pivot.

2. In a slicing machine having a knife, a feed 20 table, mechanism for advancing said feed table in relation to said knife, and a holder mounted on said feed table for the substance to be cut by said knife, means for controlling the angular position of said substance in relation to said 25 knife, comprising a lever pivoted towards one side of said feed table, said lever including a slotted portion, a pivotal connection between one end of said holder and said feed table, a link having one end adjustably engaged in said slotted 30 portion of said lever and its other end engaged with said holder at a point intermediate in the length thereof, and a stop located at the other side of said feed table, said slotted portion having its slot curved at a radius equal to the length 35 of said link and from a center coinciding with said intermediate point in the position of said holder parallel to said knife with said lever engaged by said stop.

3. In a slicing machine having a knife, a feed 40 table, a pair of vertical pillars on said feed table, mechanism for advancing said feed table in relation to said knife, and a holder for the substance to be cut by said knife, said holder being mounted on said feed table by said pillars, the combination 45 of a frame detachably secured to said pillars, a vertical pivot for said holder upon said frame towards one side of said feed table, a lever extending across said feed table above said frame, said lever including a slotted portion, a vertical 50 pivot for said lever upon said frame towards the other side of said feed table, a pivot member adjustably engaged in said slotted portion of said lever, a link connecting said holder to said pivot member, said link lying between said vertical 55 pivots, and a stop for the free end of said lever, said slotted portion having its slot curved at a radius equal to the length of said link and said stop being fixed adjacent to said first-mentioned vertical pivot.

4. In a slicing machine having a knife, a feed table, mechanism for advancing said feed table in relation to said knife, and a holder mounted on said feed table for the substance to be cut by said knife, means for controlling the angular 65 position of said substance in relation to said knife, comprising a frame detachably secured upon said feed table, a vertical pivot for said holder on said frame towards one side of said feed table, a lever pivoted on said frame towards 70 the other side of said feed table and extending across said feed table, a link connecting said holder to said lever, a stop fixed at one side of said feed table, and a tappet rod carried by said frame and slideable parallel to the advance of said 75

feed table, one end of said tappet rod being engaged by the free end of said lever, and the other end of said tappet rod adapted to engage said stop.

5. In a slicing machine having a knife, a feed table, mechanism for advancing said feed table in relation to said knife, and a holder mounted on said feed table for the substance to be cut by said knife, the combination of a frame de-
10 tachably secured upon said feed table, a vertical pivot for said holder upon said frame towards one side of said feed table, a lever extending across said feed table, a vertical pivot for said lever upon said frame, a link extending from
15 said holder in a direction away from the cutting plane of said knife and to a point upon said lever, one end of said link being adjustable in relation to the pivot of said lever, a stop located at a position approached by said feed table in
20 its advance, said stop engaging the free end of said lever in a direction to draw back said link and move said holder parallel to said knife, and disengageable means for locking said holder to said frame in a position parallel to said knife.
25. 6. In a slicing machine having a knife, a feed table, mechanism for advancing said feed table in relation to said knife, and a holder mounted on said feed table for the substance to be cut by said knife, means for controlling the angular
30 position of said substance in relation to said knife, comprising a frame detachably secured upon said feed table, a vertical pivot for said holder on said frame towards one side of said feed table, a lever pivoted on said frame towards the other
35 side of said feed table and extending across said

feed table, a link connecting said holder to said lever, a fixed stop at one side of said feed table, a tappet rod carried by said frame and slidably parallel to the advance of said feed table, a guide rod secured to said frame parallel to said tappet rod, and a block secured to one end of said tappet rod and slidable along said guide rod, the free end of said lever engaging said block, and the other end of said tappet rod adapted to engage said fixed stop.

7. In a slicing machine having a knife, a feed table, mechanism for advancing said feed table in relation to said knife, and a holder mounted on said feed table for the substance to be cut by said knife, the combination of a frame detach-
15 ably secured upon said feed table, a vertical pivot for said holder upon said frame towards one side of said feed table, a lever pivoted on said frame towards the other side of said feed table and extending across said feed table, a link con-
20 necting said holder to said lever, a fixed stop at one side of said feed table, a tappet rod carried by said frame and slidable parallel to the ad-
25 vance of said feed table, a guide rod secured to said frame parallel to said tappet rod, a block secured to one end of said tappet rod and slidable along said guide rod, the free end of said lever engaging said block, and the other end of said tappet rod adapted to engage said fixed stop, and manually disengageable means for preventing
30 movement of said tappet rod in one direction relatively to said guide rod.

ALEXANDER EDWIN PATERSON.
